US00D896340S

(12) **United States Design Patent** (10) **Patent No.:** **US D896,340 S**
Derus et al. (45) **Date of Patent:** **** Sep. 15, 2020**

(54) **AMMUNITION MAGAZINE LOADER**
(71) Applicant: **MagPump, LLC**, Henrietta, NY (US)
(72) Inventors: **Michael W. Derus**, Victor, NY (US);
Kenneth P. Green, Lunenburg, VA (US)
(73) Assignee: **MagPump, LLC**, Henrietta, NY (US)
(***) Term: **15 Years**
(21) Appl. No.: **29/650,745**
(22) Filed: **Jun. 8, 2018**
(51) **LOC (12) Cl. 22-99**
(52) **U.S. Cl.** **D22/199**; D22/108
(58) **Field of Classification Search**

(57) **CLAIM**

The ornamental design for an ammunition magazine loader, as shown and described.

DESCRIPTION

A portion of the disclosure of this patent document contains or may contain material which is subject to copyright protection. The copyright owner has no objection to the photocopy reproduction by anyone of the patent document in exactly the form it appears in the Patent and Trademark Office patent file or records, but otherwise reserves all copyrights whatsoever.

FIG. 1 is a front elevation view of the ammunition magazine loader.

FIG. 2 is a rear elevation view of the ammunition magazine loader.

FIG. 3 is a left side elevation view of the ammunition magazine loader.

FIG. 4 is a right side elevation view of the ammunition magazine loader.

FIG. 5 is a top view of the ammunition magazine loader.

FIG. 6 is a bottom view of the ammunition magazine loader.

FIG. 7 is a left isometric view of the ammunition magazine loader; and,

FIG. 8 is a right isometric view of the ammunition magazine loader.

The dashed, broken lines in the drawings are shown for illustrative purposes only and form no part of the claimed design. The long-short-long, broken lines in the drawings define the bounds of the claimed design and form no part of the claimed design.

1 Claim, 8 Drawing Sheets
